UNITED STATES PATENT OFFICE

THERON T. CHAMBERLAIN, OF CHICAGO, ILLINOIS, ASSIGNOR OF ONE-HALF TO CHESTER THOMAS HANLEY, OF CHICAGO, ILLINOIS

CASEMENT WINDOW AND HINGE THEREFOR

Application filed December 10, 1930. Serial No. 501,206.

The invention has reference to casement windows or like constructions embodying hinges adapted to permit of a dual movement of one constructional part relative to another.

An object of the invention is to provide a novel construction of this character in which a hinge of improved character guides the movement of one part relative to the other 10 in one direction and subsequently supports said part during further relative movement in another direction.

More specifically stated, an object of the invention resides in the provision of a casement window or similar construction in which what may be termed the movable closure member has a sliding movement relative to a frame to free the parts from an inter-engaging relationship before a pivotal movement of the parts is possible, said closure member being supported by hinges fashioned to permit of such sliding movement only when the parts are in their closed relationship, and to guide and support the movable closure in all movements thereof relative to said frame.

A further object of the invention is to provide a hinge member of new and improved construction for use in connection with casement windows or like structures.

More particularly, another object is to provide a novel hinge construction embodying two hinge members connected by a pintle and curl arrangement including a projecting part on the pintle-carrying member adapted to engage said curl to support the members in more than one position of relative pivotal movement, said members having one position in which said curl and said part are not engaged to permit of a relative movement of said members in a direction paralleling the axis of said pintle.

Other objects and advantages will become apparent in the following description and from the accompanying drawing, in which:

Figure 1 is a front elevation of a casement window construction embodying the features of the present invention.

Fig. 2 is a fragmentary front elevation, on an enlarged scale, showing a hinge member.

Fig. 3 is a transverse section of a hinge member showing the parts in the position assumed when the window is closed.

Fig. 4 is a front elevation of a modified form of hinge.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawing, a casement window is shown, for the purposes of illustration, which comprises a frame member 10 and a closure or window member 11 arranged to fit relatively snugly therein. In such constructions, the window 11 is mounted for swinging or pivotal movement relative to the frame and a common disadvantage inherent thereto is due to the difficulty in adequately sealing the gap between the lower portion of the window and the bottom portion of the frame to prevent the entrance of air and moisture. In the present instance, this disadvantage is overcome by providing a traversing member or stool 12 extending across the bottom of the frame adjacent the space occupied by the lower portion of the window and on the side thereof toward which the window swings. The window-receiving recess in the frame 10 is somewhat longer than the window to allow the window to slide with respect to the frame to carry the window free or clear of the upper edge of the stool. This sliding movement precedes the pivotal movement of the window in opening it and follows such movement in closing the window.

Means is provided in the form of hinge members for supporting said window in the frame, which members are arranged to guide and support the window in its aforesaid dual movement. With particular reference to Fig. 2, a preferred form of hinge is illustrated as comprising a pair of hinge leaves or plates 13,

14 apertured in the usual manner to permit of their being secured to the frame 10 and window 11 respectively. One of the hinge plates, in this instance the plate 13, carries laterally spaced, transversely extending bosses 15 between which a pintle 16 extends. The pintle preferably is secured rigidly to the bosses in any suitable manner as by upsetting the extending ends of the pintle. The other hinge plate 14 carries one or more (in this instance two) transversely extending, relatively narrow curls 17 which are located intermediate the ends of the plate to engage the pintle at spaced points between the bosses 15.

The arrangement and disposition of the parts is such that, in addition to relative pivotal movement of the hinge plates, a relative sliding movement thereof, in a direction paralleling the pintle axis, is permitted. When such a hinge is used in connection with casement window constructions of the character described, the extent of such sliding movement is slightly greater than the length of movement necessary to cause the window to clear the stool.

Means is provided for positively supporting the hinge plates for pivotal movement in various of their relative axial positions, which means is automatically engaged or disengaged as said plates move relatively out of or into one position. In this instance, this means comprises one or more lugs 18 formed integrally with the pintle-carrying plate 13 to extend toward the pintle into a position where the curls 17 may be engaged thereby. Herein two such lugs are shown as being located substantially centrally of one side of the hinge plate 13 and spaced from each other a distance slightly greater than the width of one of the curls. Moreover, the lugs are so proportioned that in one position of the plates 13, 14 the lugs may enter the space between the curls 17. The curls, as may be seen in Figs. 2 and 3, are not completely closed, thereby providing gaps or recesses 19 therein through which the lugs 18 may slide when the faces of the hinge plates are abutting.

In operation, the hinge plates are first properly secured to the frame and window (see Fig. 1) so that the faces of the plates will be in abutment when the window is closed. As a result, the window is free to move vertically of the frame, the hinges, in such movement, acting as guides. As the window approximates the top limit of its vertical movement to clear the stool 12, the relative axial movement of the hinge plates disposes one of the curls 17 opposite the space between the lugs 18. Upon subsequent pivotal movement of the window, said opposed lug is turned to enter said space and rest upon the lower lug for supporting the window for swinging in its elevated position. It will be evident that, in this position, relative axial

movement of the hinge plates is positively prevented and the window is held out of contact with the stool to prevent injury thereto.

When the window is closed, the interengagement between the lugs and curl is maintained until the window is completely closed, whereupon the recesses 19 allow the curls to slip past the lugs to permit the window to return automatically to its closed position.

If desired, this hinge construction may be employed where three positions of swinging movement are desired. Thus, the hinge plates may be moved relatively to dispose the upper curl between the lugs thereby providing a second position, or the plates may occupy an intermediate position in which the two curls are disposed on opposite sides of the two lugs. Consequently, hinge members of this type may be employed interchangeably on either side of the window. It is, of course, obvious that one or more than two lugs, or curls, or both, may be employed without materially altering the structure.

Figure 4 illustrates a somewhat modified form of hinge structure. In this form, the general arrangement of hinge plates 13, 14, bosses 15, pintle 16, and curls 17 is unchanged except that each curl has an intermediate, arcuately formed recess 20 therein extending from the free end of the curl. A single centrally located lug 21 is carried by the hinge plate 13 and is shaped and disposed to enter one or the other of said recesses 20 depending upon the axial relation of the hinge plates. The operation of this form is substantially similar to that of the hinge shown in Fig. 2.

From the foregoing, it will be apparent that a novel construction for a casement window or the like has been provided which embodies an improved form of hinge device adapted to guide a movement of the window in the plane thereof and subsequently to support the window for pivotal movement in one of its various positions. Furthermore, such operation of the device is entirely automatic. The structure involved is exceedingly simple and the hinge parts may be formed by a die-casting operation whereby the hinge may be manufactured and sold at a low cost.

I claim as my invention:

1. A hinge comprising, in combination, a pair of hinge plates, a pintle rigid with one of said plates, a pair of spaced curls on the other of said plates engaging said pintle intermediate the ends thereof to permit of axial movement of said curls along said pintle, and a pair of lugs on said pintle-carrying plate extending therefrom into the path of axial movement of said curls, said curls having recesses therein arranged in one relative pivotal position of said plates to permit said curls to pass said lugs, said lugs being spaced apart a distance greater than the width of one of said curls to receive one of said curls therebetween upon pivotal

movement of said plates out of the position in which the curls may pass the lugs.

2. A hinge comprising, in combination, a pair of hinge plates, a pintle rigid with one of said plates, pintle-engaging curls carried by the other of said plates and disposed for axial sliding and pivotal movement relative to the pintle, projecting means on the pintle-carrying plate arranged to engage said curls to prevent said axial movement and to support said plates in several relative axially shifted positions, said curls having recesses therein to permit passage thereof past said projecting means as the plates are shifted from one to another of said positions.

3. A hinge comprising, in combination, a pair of hinge plates, a pintle rigid with one of said plates, pintle-engaging curls carried by the other of said plates and disposed for axial sliding and pivotal movement relative to the pintle, projecting means on the pintle-carrying plate arranged to engage said curls to prevent said axial movement when the plates are in one of several relative axially shifted positions, said curls being partially open to provide a recess therein through which said projecting means may pass when said plates are shifted axially while in face-abutting relation.

30 4. A hinge comprising, in combination, a pair of hinge plates, a pintle rigid with one of said plates, a curl carried by said other plate and embracing said pintle, said curl being arranged to slide axially of said pintle and having an arcuate recess therein, and a projection on said pintle-carrying plate fashioned to engage said recess to prevent said axial movement, said curl having a second and transversely extending recess communicating with the first mentioned recess to permit disengagement of said projection from said arcuate recess in one relative pivotal position of the plates.

In testimony whereof, I have hereunto affixed my signature.

45 THERON T. CHAMBERLAIN.
